UNITED STATES PATENT OFFICE.

LOUIS B. GOLDBERG, NATHAN GOLDBERG, WILLIAM GOLDBERG, AND JACOB M. GOLDBERG, OF DENVER COLORADO.

COMBINED TABLE AND CAMP-STOVE SUPPORT.

Application filed May 22, 1924. Serial No. 715,115.

To all whom it may concern:

Be it known that we, LOUIS B. GOLDBERG, NATHAN GOLDBERG, WILLIAM GOLDBERG, and JACOB M. GOLDBERG, citizens of the United States, residing at Denver, the city and county of Denver and State of Colorado, have invented certain new and useful Improvements in Combined Table and Camp-Stove Supports; and we do declare the following to be a full, clear, and exact description of the invention such as will enable others skilled in the art to which it appertains to make and use the same, reference being had to the accompanying drawings, and to the characters of reference marked thereon, which form a part of this specification.

This invention relates to a combined table and camp stove support.

Owing to the great and ever increasing popularity of camping, especially by automobileists, it has been necessary to devise camping equipment that can be readily transported and which will be of rugged and substantial construction. Camp stoves employing gasoline as fuel have been perfected and are in extensive use. It is, however, very desirable to have a stand or support of some kind for supporting the stove at the proper height above the ground for convenience in cooking. It is also desirable to have a table in close proximity to the stove.

It is the object of this invention to provide a support that can be employed in connection with a camp stove, provided with legs bent in a peculiar manner so as to cooperate with the support for the purpose of holding the stove securely in place.

It is a further object of this invention to produce a stove support that is so constructed that an extension for the support of a table may be attached to one side of the stove support. The extension is so constructed that another extension may be added to it and thereby enabling a table to be built of any desired length.

In order better and more clearly to describe our invention, we shall have reference to the accompanying drawings in which the preferred embodiment of our invention is shown, and in which:

Fig. 1 is a perspective view of our improved support showing the stove mounted thereon and showing also one of the table supporting extensions;

Fig. 2 is a section taken on line 2—2, 55 Fig. 1;

Fig. 2^a is a section taken on line 2^a—2^a, Fig. 2;

Fig. 3 is a section taken on line 3—3, 60 Fig. 1;

Fig. 4 is a view of the upper end of one of the stove support legs, this view being taken in the direction of the arrow 4 in Fig. 2;

Fig. 5 is a view taken along line 5—5, 65 Fig. 1, and shows the manner in which the lower end of the diagonal brace is formed;

Fig. 6 is a view showing one side of the support in folded position;

Fig. 7 is a section through the top of one 70 of the legs of the stove supports and shows the manner in which the table support extension is attached thereto;

Fig. 8 is a fragmentary side elevation of the table-supporting extension, showing the 75 use of toggles;

Fig. 9 is a perspective view with parts broken away of a table which is formed in part by our stove support; and

Fig. 10 is a detail showing a supporting 80 member.

Numeral 1 represents the body of the camp stove, 2 represents the cover, and 3 the legs which are pivoted at 4 to the sides of the stove. The ends of the legs are bent 85 into V-shape, the apex being U-shaped, as indicated by numeral 5 in Figs. 2 and 2^a. The purpose of this peculiar construction will appear as the description proceeds.

The support or stand comprises four legs, 90 indicated as 6 and 6^a. The legs similarly numbered being identical. The legs are connected near their upper ends by straps 7, 8 and 9, 10. Straps 7 and 8 are pivoted at 11, while straps 9 and 10 are pivoted at 12. The 95 outer ends of each pair of straps are pivoted to the legs at 13. Pivots connected to straps 7 and 8 at points 14, substantially midway between the pivots 11 and 13, are straps 15 whose upper ends are pivoted together at 16. The lower ends of straps 15 are provided with rivets 17 that are slidable in the slots 18 of the support legs. When the support is to be used, the legs 6 are moved apart into the position shown in Fig. 105 1. In this position straps 7, 8 and 9, 10 are straight and serve as toggles to prevent the legs being moved together. When the stand

is to be transported, it is collapsed into the shape shown in Fig. 6. Secured to the sides of the legs 6^a, near the top, are straps 18 that may be held in place by any suitable means such as spot welding. This forms a triangular opening (Fig. 2) for the reception of the U-shaped portion 5 of the stove legs 3. The function of the U-shaped portion will now be apparent, as they cooperate with the opening in the upper end of the legs to hold the stove securely in place. The U-shaped ends of the legs 3, therefore, cooperate with the openings in the support legs to produce a desirable result. The camp stoves of the type herein referred to are usually provided with hinged covers 2. When the stove is in use, the cover must, of course, be held in open position. For the purpose of supporting the cover in open position, we have provided two bars 19 which are pivoted at 13. The lower end of these bars is split so as to provide two fingers 20 and 21. The part 21 is offset so that one of the bars 15 may be received between the fingers in the manner shown in Fig. 1 in which the bar 19 is shown in operative position. Each one of the support legs are provided near their upper ends with openings 22 for the reception of the hooked end 23 of the table-supporting bar 24. These bars are pivoted at 25 to the upper ends of legs 26 and 26^a that correspond in construction and function with legs 6 and 6^a and may, in fact, be identical with these, although only a single slot 18 is needed. These extensions can be hooked onto the stove support in the manner shown and when it is found necessary or desirable, several extensions may be connected in series, as indicated by dotted lines. If it is found necessary or desirable, the bars 24 may be connected to the legs 26 and 26^a by means of a toggle composed of links 27 and 28 in the manner shown in Fig. 8.

Our improved support can also be employed to support a table top by a very simple modification. The support is not modified in the least, but two rods 29 are provided, each of which has its end portions 30 bent at right angles. The ends 30 are inserted into the openings in the ends of the

legs where the U-shaped portions 5 of the stove legs are received when the stove is to be supported. Instead of the extension described above, we may use one consisting of an angle iron 31 to the ends of which the side members 32 are pivotally attached. The side members have end portions 33 provided with notches N. These ends are inserted into the openings 22. Diagonal braces 34 are pivoted to the sides 32 at 35 and have ends 36 of reduced width which enter openings 37 in the supporting legs. A table top 38 of thin slats or boards properly connected together is laid on the parallel bars 29 and 32, thereby forming a table.

It is evident that the support shown in Fig. 9 may be readily collapsed and folded into a small package.

In order to prevent the bar 19 from exerting a force tending to collapse the support, we have provided the bar 15 with a notch 191 that provides a shoulder which serves as a stop for the end of bar 19 (Figs. 1 and 6).

Having now described our invention, what we claim as new is:

1. A support comprising, in combination, four legs connected to each other in a rectangular formation, each leg being connected to two other legs by hinged straps whose ends are pivotally connected to the legs, said straps being adapted to be extended into straight position for the purpose of properly spacing the legs, and means for holding the legs in predetermined angular relation when in extended position, said means comprising pairs of straps, said last named straps being pivotally connected intermediate their ends to the first mentioned straps at points intermediate the ends of the first mentioned straps.

2. A device in accordance with claim 1 in which the legs have openings in their upper ends for the reception of the U-shaped ends of stove legs.

In testimony whereof we affix our signatures.
